DESIGN FOR A MENDING TREE

Frank C. Salagie, Los Angeles, Calif.

Substituted for abandoned application Serial No.
101,593, June 21, 1941. This application August
7, 1944, Serial No. 114,765

Term of patent 7 years

(Cl. D3—19)

To all whom it may concern:

Be it known that I, Frank C. Salagie, a citizen of the United States, residing at 239 East Colden Avenue, in the city and county of Los Angeles, postal zone 3, and State of California, have invented a new, original, and ornamental Design for a Mending Tree, of which the following is a specification, reference being had to the accompanying drawing, forming part thereof.

Figure 1 is a perspective view of the mending tree, showing my design.

Figure 2 is a plan view of the same.

The instant application is a substitute application for my abandoned application, Serial Number D101,593, filed June 21, 1941.

I claim:

The ornamental design for a mending tree, as shown.

FRANK C. SALAGIE.
